UNITED STATES PATENT OFFICE.

PETER CHATELAIN, OF BOSTON, MASSACHUSETTS, ASSIGNOR TO M. H. DRYFOOS & CO., OF SAME PLACE.

DESIGN FOR A GLOVE.

SPECIFICATION forming part of Design No. 25,050, dated January 14, 1896.

Application filed December 13, 1895. Serial No. 572,092. Term of patent 14 years.

To all whom it may concern:

Be it known that I, PETER CHATELAIN, of Boston, in the county of Suffolk and State of Massachusetts, have invented and produced 5 a new and original Design for Gloves, of which the following is a specification, reference being had to the accompanying drawing, which shows a glove embodying my design.

The leading feature of the design consists 10 in a glove having an opening or slit extending at the side from the back edge of the glove along the wrist portion and terminating short of the hand portion, and two flaps extending along the wrist portion, one at 15 each side of the said opening, the flaps projecting beyond the side edge of the hand portion and likewise terminating short of said hand portion.

The glove as shown has a hand portion A 20 and a wrist portion B. From the back edge B' of the glove a slit or opening extends lon-

gitudinally of the wrist portion B at the side thereof to a point C at or near the end of the hand portion A, so that the lateral opening practically terminates short of the hand portion. The forward end of the slit at C, as shown, is at the inner end of the side edge A' of the hand portion. At each side of the said slit or opening a flap D or D', respectively, extends along the wrist portion B and beyond the side edge A' of the hand portion A, the flaps likewise terminating at C—that is, short of the hand portion. The flaps D and D' carry the fasteners E and E', respectively. 30 35

I claim—

The design for a glove, substantially as hereinbefore described.

PETER CHATELAIN.
